UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

AUDIBLE SIGNAL FOR RAILWAY BRAKING APPARATUS.

Application filed July 17, 1926. Serial No. 123,025.

My invention relates to railway automatic train control apparatus, and particularly to apparatus of the type wherein a time interval elapses after a stop indication is received before a brake application is incurred. One feature of my invention is the provision of means for giving an audible signal during this time interval, so that the engineer may be on the alert to prevent an automatic brake application by reducing the speed or acknowledging the restrictive indication.

I will describe one form of apparatus embodying my invention, and will then point out the novel features thereof in claims.

The accompanying drawing is a view showing one form of apparatus embodying my invention.

Referring to the drawing, the apparatus here illustrated, all of which is carried on a railway train, comprises a reservoir A, which is normally charged with fluid pressure to prevent an automatic brake application, but the pressure in which is reduced to brake applying value under unsafe traffic conditions at a rate dependent upon the speed of the train. Usually this reservoir will be so controlled that as the speed of the train decreases, the rate of pressure reduction decreases. For example, if the restrictive signal indication is received when the speed is 30 miles per hour, the brake application may be incurred 5 seconds thereafter, while if the restrictive signal indication is received while the speed of the train is 20 miles per hour the brakes may apply 40 seconds thereafter, the delay period being of proportionate intermediate values at speeds intermediate the limits specified.

One form of apparatus for controlling this reservoir in the manner specified and for causing a brake application when the pressure in the reservoir is reduced to a given value, is shown in United States Letters Patent Reissue No. 16,083, granted to Frank H. Nicholson on May 26, 1925, wherein two such reservoirs are disclosed, one of which is designated T^H and the other of which is designated T^M.

The reference character B designates a whistle, and the reference character C designates a whistle-operating reservoir. The supply of fluid pressure from the reservoir A to the reservoir C and subsequently from

the reservoir C to the whistle B is controlled by a valve D.

The valve D comprises a body member 3 having a chamber 12 provided with two oppositely disposed seats 6 and 8. The relatively small seat 6 communicates with the whistle B through a port 5 and a restricted orifice 7, while the relatively large seat 8 communicates with the brake controlling reservoir A through a port 9 and pipes 2 and 1. The chamber 12 communicates with the whistle operating reservoir C by a pipe 4. Located in the chamber 12 is a diaphragm designated as a whole by the reference character 10, and comprising a central position normally engaging the valve seat 6, as well as a thin flexible flange normally resting on the valve seat 8. The entire diaphragm is preferably made of rubber. This diaphragm is normally in the condition shown in the drawing, wherein both the ports 9 and 5 are closed, but it may bulge downwardly as a whole to open the port 5 to chamber 12 and so to reservoir C, and the flange 10^b may also bend upwardly to open communication between the port 9 and the pipe 4.

I will first assume that the brake controlling reservoir A is at atmospheric pressure and that the pressure in this reservoir is then increased. As the pressure in reservoir A increases, the flange 10^b of the diaphragm 10 will bend upwardly to admit pressure to reservoir C, so that when the pressure in reservoir A reaches its maximum value the reservoir C will contain fluid pressure at substantially the same value. During this time the portion 10^a of the diaphragm 10 has remained in contact with the valve seat 6 so that the whistle B has been silent. I will next assume that a restrictive indication is received, so that the pressure in the reservoir A decreases. The pressure above the valve member 10 is now greater than that below this member, so that the diaphragm 10 bulges downwardly away from the valve seat 6, thereby admitting fluid pressure from the reservoir C to the whistle B and sounding this whistle to inform the engineer that a restrictive indication has been received. The whistle will blow as long as the pressure in reservoir A continues to reduce, and during this time the engineer may either reduce the speed below the

value required by the particular indication which has been received, or he may take other steps to prevent an automatic application of the brakes. One form of apparatus whereby the engineman may prevent a brake application during the interval that the whistle is blowing is shown and described in the aforesaid Nicholson Reissue Patent No. 16,083.

10 Preferably a gauge E is connected with the reservoir A by pipes 11 and 1 to show the engineman the actual pressure in this reservoir and to inform him as to approximately how long he may wait after a restrictive indication is received before taking steps to prevent an automatic application of the brakes.

Although I have herein shown and described only one form of apparatus embodying my invention, it is understood that various changes and modifications may be made therein within the scope of the appended claims without departing from the spirit and scope of my invention.

25 Having thus described my invention, what I claim is:

1. Train carried governing apparatus comprising a brake controlling reservoir which is normally charged with fluid pressure to prevent automatic application of the brakes but the pressure in which is reduced to brake applying value under unsafe traffic conditions at a rate dependent upon the speed of the train, a whistle, a whistle operating reservoir, a valve having a chamber communicating with said whistle and with said two reservoirs, and a flexible diaphragm in said chamber for connecting said whistle operating reservoir with said brake controlling reservoir while the pressure in the latter is increasing and for connecting the whistle operating reservoir with the whistle while the pressure in the brake controlling reservoir is decreasing.

45 2. Train carried governing apparatus comprising a brake controlling reservoir which is normally charged with fluid pressure to prevent automatic application of the

brakes but the pressure in which is reduced to brake applying value under unsafe traffic 50 conditions at a rate dependent upon the speed of the train, a whistle, a whistle operating reservoir, a valve having a chamber communicating with said whistle operating reservoir and provided with two oppositely 55 disposed seats communicating respectively with said whistle and said brake controlling reservoir, and a flexible valve member normally engaging both of said seats but capable of bending to permit charging the whistle 60 operating reservoir while the pressure in the brake controlling reservoir is increasing and capable of bulging away from the whistle seat to vent the whistle operating reservoir to the whistle while the pressure in the brake 65 controlling reservoir is decreasing.

3. Train carried governing apparatus comprising a brake controlling reservoir which is normally charged with fluid pressure to prevent automatic application of the 70 brakes but the pressure in which is reduced to brake applying value under unsafe traffic conditions at a rate dependent upon the speed of the train, a whistle, a whistle operating 75 reservoir, a valve having a chamber communicating with said whistle operating reservoir and provided with two oppositely disposed seats communicating respectively with said whistle and said brake controlling reservoir, the whistle seat being relatively 80 small, and the other seat being relatively 85 large, and a diaphragm having a central portion normally engaging said whistle seat and a flexible flange normally engaging the other seat, said flange being capable of bending inwardly to permit charging the whistle operating reservoir while the pressure in the brake controlling reservoir is increasing, and said flange being also capable of permitting the central portion to bulge away from the seat to vent the whistle operating reservoir to the whistle while the pressure in the brake 90 controlling reservoir is decreasing.

In testimony whereof I affix my signature.

LLOYD V. LEWIS.
